MACHINE FOR OPERATING ON THE SOLES
OF SHOESJames P. Fredericksen, Braintree, Mass., assignor
to United Shoe Machinery Corporation, Flem-
ington, N. J., a corporation of New Jersey

Application October 3, 1945, Serial No. 620,047

10 Claims. (Cl. 12—18)

1 My invention relates to machines by which various operations may be performed on the soles of shoes, such as rounding to their approximate peripheral contour or the formation of channels to receive the stitching for their attachment. It is especially applicable to the well-known Good-year Universal rounding and channeling machine, model E, which is, in most respects, as disclosed in Letters Patent of the United States No. 1,030,606, Perry, June 25, 1912.

In a machine of the character of that above indicated, means is provided for varying the path along which the rounding, channeling or other tools act upon a sole having preliminary attachment to a shoe-bottom. A guide engages the crease between the upper and the welt along the shank of the shoe, and a second guide engages the shoe-upper along the forepart. The change from crease-guide to forepart-guide is effected by movement of the latter, and the present invention fully overcomes a difficulty encountered when operating at the inside of the right shoe and when the projecting edge of the sole being rounded is to be narrower at the forepart than at the shank. Under these conditions, there is a tendency, as the forepart-guide is lowered in approaching the ball-line, for the crease-guide to rise prematurely before the forepart-guide is in control of the work. An unduly narrow shank-edge will result, so the outsole-stitcher may run off the welt or the inseam may be cut in the trimming of the edge. This trouble has been recognized and partially corrected by mechanism disclosed in Letters Patent of the United States No. 1,331,789, Smith, February 24, 1920. Here, a member is interposed between contact-abutments upon the forepart-guide-lever and crease-guide-lever to hold the crease-guide temporarily down. The member is gradually retracted as the forepart-guide is lowered for engagement with the shoe-upper, until, as said guide approaches its final position, the member reaches a point at which it so leaves the abutments that the crease-guide is abruptly lifted by its spring, giving the forepart-guide control. This arrangement has a substantial effect in delaying the rise of the crease-guide, but it is a frequent practice of operators of the machine to depress the treadle, through which the forepart-guide is lowered, considerably before the ball-line is reached. During the advance of the work from that point, the member cannot hold down the crease-guide for a sufficient time and an unduly narrowed shank-edge results. The difficulty is increased, because the distance of the forepart-guide from the fulcrum of its supporting lever is

2 much less than that of the crease-guide from its lever-f fulcrum. Consequently, the rate of movement of the forepart-guide is rapid as compared with that of the crease-guide, tending, if the forepart-guide is lowered prematurely, to hasten improper narrowing of the shank-edge. It is further to be noted, that, in the patented mechanism, in which the position-controlling member interposed between the guide-levers receives its movement through direct connection to the forepart-lever, said position-controlling member is swung upwardly as well as outwardly from between the abutments. This tilting of the member forces the crease-guide down before it has an opportunity to rise, so there is at once some narrowing of the shank-edge. The effect of all these factors is to prevent any definite relation between the arrival of the forepart-guide in its work-engaging position and the release of said work by the crease-guide, and to render it extremely difficult for the operator to initiate the change in the sole-edge in the correct relation to the ball-line. It is an object of the present invention to exercise such control over the crease-guide that it can have no movement away from the work until the forepart-guide is in the desired work-positioning relation.

In the attainment of the above object, I combine with a forepart-guide and a crease-guide movable as above indicated, means for securing the crease-guide against movement from its work-engaging position until the forepart-guide has fully reached such position and means for thereafter moving the securing means to release the crease-guide. By thus fixing the crease-guide during the descent of the forepart-guide, the transfer of control from the former guide to the latter can be made quite accurately at the desired time, and in the correct relation to the ball-line. The means by which the crease-guide is thus secured is here shown as including a member, preferably in the form of a slide, movable independently of the forepart-guide and preferably also movable with said guide. As is desirable, the time of control of the crease-guide by the member is made variable. The securing member extends between contact-portions or abutments upon the levers which carry the guides and may be retained against movement by such a device as a latch, which, being independent of the guides, is not directly affected by their movement. It is, however, released by means controlled with the forepart-guide and is then retracted to free the crease-guide for movement from the work.

55 In the accompanying drawing,

Figs. 1 and 2 illustrate, in a fragmentary manner, in side elevation, the elements of a rounding and channeling machine more directly involved in the present invention, and respectively showing the crease-guide and the forepart-guide in their active positions.

Mounted upon a frame 10 is a reciprocating rounding knife 12 operating against an oscillatory feed-point carried by a feed-arm 14. Co-operating with the feed-point to advance the work to receive the action of the knife is a bottom-rest 16, this rest being engaged by the tread-surface of a shoe-sole being operated upon, the feed-point contacting with the upper face of the welt. Fulcrumed upon the frame about an axis indicated at 18 is a lever, the supporting yoke of which appears at 20. On the outwardly projecting arm 22 of the lever is carried the forepart guide 24, the end-surface 26 of which is adapted to receive contact of the upper of a shoe being operated upon just above the crease between said upper and a preliminarily attached sole, and thereby determine the relation of the sole-edge to the knife 12. The degree of extension of the guide below the lever-arm, and therefore the width of the sole-edge when the guide is in its active position, is determined by adjusting mechanism 28. A spring 30 joining an arm 32 of the lever 20 to the frame holds the arm 22 normally raised against a stop-surface 34 upon the frame. The depression of the lever to carry the guide to its active work-engaging position is produced through a link 36 connecting the yoke to one arm of a bell-crank-lever 40, to a second arm of which is joined a rod 42 leading to an unillustrated treadle. When lowered, the guide 24 is controlled by cam mechanism 44 which does not enter directly into this invention. In the movement of the guide 24, it rests yieldably against the outer face of the feed-arm 14. Fulcrumed at 46 upon the frame is a lever 48, to the outer extremity of which is secured a guide 50 in the form of a loop, between the arms of which the feed-point operates. The lower edge 52 of the loop is adapted to enter the crease between the sole and the shoe-upper. The lever 48 has a curved abutment-surface 54, which is shown as furnished by the upper edge of a plate 56 attached to the lever by a slot-and-screw connection 58. The abutment-surface 54 is drawn by a tension-spring 60, joining the lever 48 to the frame, yieldably toward an abutment-roll 62 rotatable upon a bracket 64 secured to the lever 20, there being interposed between the abutments a slide or controlling member 65, to be described later. By this engagement, the work-controlling position of the guide 50 is determined, and this may be altered by adjustment of the plate 56 through its connection 58. The axis of the roll 62 preferably coincides with the axis 18 of the fulcrum of the lever 20, so, as the lever oscillates, the roll has no movement of translation. As the guide 24 is lowered through the action of the treadle-rod 42, the guide 50 first remains at rest until a screw 66, adjustable upon the lever-arm 22, strikes a contact-surface 68 upon the lever 48. Thereafter the two guides descend together.

It is desired that, when a change is to be made in the sole-edge extension at the inside of a right shoe from a certain width at the shank to a less width at the forepart, this shall take place substantially at the ball-line, and that the normal width at the shank shall not be narrowed. My invention accomplishes this in the following manner. The opposite surfaces of the end 70 of the

slide 65, with which contact the abutments 56 and 62, are parallel to each other and extend horizontally, being maintained in this position by a projection 74 from the opposite extremity of the slide and lying in an arcuate opening 76 in a depending arm 78 of the bell-crank-lever 40. A tension-spring 80 joining the inner end of the slide to the frame urges said slide toward the left, tending to withdraw it from between the abutments. It is, however, held against this withdrawal to maintain a normal relation between the guides 24 and 50 by a latch 82 fulcrumed upon a bracket 84 fixed to the frame and forced up by a torsion-spring 86, so it lies in a depression 87 in the under side of the slide (Fig. 1). As the work, governed as to its vertical position and relation to the knife 12 by the guide 50 lying in the crease of the shoe at the shank, advances so the ball-line approaches the guide, the operator, through the rod 42, lowers the guide 24. The slide 65 is held against movement by the latch 82, the opening 76 in the guide-actuating bell-crank-lever 40 traveling idly along the slide-projection 74, while the abutment-roll 62 turns, without bodily movement, about the axis 18 of the lever 20. The guide 50 is therefore held positively against upward displacement, and the full width of the sole-extension at the shank is maintained undisturbed, even if the actuation of the rod 42 had been premature. When the surface 26 of the descending forepart-guide is so approaching the end of the crease-guide that it is in proximity to the shoe-upper and is ready to take control of the work, a screw 88, threaded through an extension 90 of the lever-arm 78 and which has been traveling idly during the lowering of the forepart-guide, strikes the tail 92 of the latch 82. This withdraws the latch from the depression 87 in the slide 65, which, when thus freed, is drawn to the left by the spring 80, until it is stopped by engagement of the slide-projection 74 with the left-hand end of the opening 76 (Fig. 2). The end 70 of the slide is thus retracted from between the abutments 56 and 62, allowing the spring 60 to raise the guide 50 from the crease. The movement of withdrawal of the slide is rectilinear, without any angular component which would tend to displace the crease-guide so the sole would be narrowed. The movement is limited by the engagement of the abutment-surface 54 with the abutment-roll 62. This leaves the surface 26 of the guide 24 in contact with the shoe-upper and in complete control of the width of the sole-extension during the operation upon the forepart. The crease-guide, in the meantime, has held the work continuously against movement which would have narrowed the shank. By adjusting the extent of projection of the screw 88 from the lever-extension 90, there may be varied the time of release of the crease-guide, and its elevation, with respect to the lowered position of the forepart-guide. When the operator frees the treadle and the forepart-guide rises to again leave the work positioned by the crease-guide, the screw 88 is separated from the tail of the latch 82, allowing the spring 86 to lift said latch against the under side of the slide. As the lever-arm 78 turns counterclockwise, the left-hand end of the opening 76, acting upon the projection 74, forces the end of the slide back between the abutments, the curved surface 54 and that of the roll 62 facilitating its entrance. At the same time, the slide-spring 80 is tensioned. The crease-guide 50 is lowered by the entrance 75 of the slide to its normal active position.

Having thus described my invention, what I claim as new and desire to secure by Letters Patent of the United States is:

1. In a machine for operating upon the soles of shoes, a guide for engagement with the crease of a shoe, a guide for engagement with the forepart of a shoe, said guides being movable into and out of work-engaging position, means for securing the crease-guide against movement from its work-engaging position until the forepart-guide has fully reached its work-engaging position and means for thereafter moving the securing means to release the crease-guide.

2. In a machine for operating upon the soles of shoes, a movable forepart-guide, means arranged to move the forepart-guide into work-engaging position, a crease-guide positioned by the forepart-guide for engagement with the work, means for moving the crease-guide out of work-engaging position, and means including a member movable after the work engaging movement of the forepart-guide for controlling the movement of the crease-guide out of work-engaging position.

3. In a machine for operating upon the soles of shoes, a movable forepart-guide, means arranged to move the forepart-guide into work-engaging position, a crease-guide positioned by the forepart-guide for engagement with the work, means for moving the crease-guide out of work-engaging position, and means including a member movable with the forepart-guide and independently thereof for controlling the movement of the crease-guide out of work-engaging position.

4. In a machine for operating upon the soles of shoes, a movable forepart-guide, means arranged to move the forepart-guide into work-engaging position, a crease-guide positioned by the forepart-guide for engagement with the work, means for moving the crease-guide out of work-engaging position, means including a member movable independently of the forepart guide for controlling the movement of the crease-guide out of work-engaging position, and means arranged to vary the time of control of the crease-guide by the member.

5. In a machine for operating upon the soles of shoes, a movable forepart-guide, means arranged to move the forepart-guide into work-engaging position, a crease-guide positioned by the forepart-guide for engagement with the work, a movable member through which movement of the forepart-guide is communicated to the crease-guide, means independent of the guides for retaining the member against movement, and means controlled by the forepart-guide for releasing the member from the retaining means.

6. In a machine for operating upon the soles of shoes, a movable forepart-guide, means arranged to move the forepart-guide into work-engaging position, a crease-guide positioned by the forepart-guide for engagement with the work, a movable member through which movement of the forepart-guide is communicated to the crease-guide, means independent of the guides for retaining the member against movement, means controlled by the forepart-guide for releasing the member from the retaining means, and means

arranged to vary the time at which the forepart-guide releases the retaining means.

7. In a machine for operating upon the soles of shoes, a movable forepart-guide, means arranged to move the forepart-guide into work-engaging position, a movable crease-guide, there being opposite abutments movable with the two guides, a member movable between the abutments to determine the normal relation between the guides, a latch by which the member is initially retained between the abutments, means for releasing the member from the latch, and means for retracting the released member from the abutments.

15 8. In a machine for operating upon the soles of shoes, a movable forepart-guide, means arranged to move the forepart-guide into work-engaging position, a movable crease-guide, there being opposite abutments movable with the two guides, a member movable between the abutments to determine the normal relation between the guides, a latch by which the member is initially retained between the abutments, a member movable with the forepart-guide into contact with the latch to release the relation-determining member, there being means arranged to render the latch-releasing member ineffective during a portion of its movement, and means for retracting the released member from the abutments.

25 9. In a machine for operating upon the soles of shoes, a lever carrying a forepart-guide and being provided with an opening, means arranged to move the forepart-lever, a lever carrying a crease-guide, the two levers having opposite contact-portions, means for urging the contact-portion of the crease-guide-lever toward that of the forepart-guide-lever, a slide movable between the contact-portions of the two levers and having a projection extending into the forepart-lever-opening, means for retracting the slide, means for retaining the slide against retraction, and means movable with the forepart-lever for releasing the slide from the retaining means.

35 10. In a machine for operating upon the soles of shoes, a lever carrying a forepart-guide and being provided with an opening, means arranged to move the forepart-lever, a lever carrying a crease-guide, the two levers having opposite contact-portions, means for urging the contact-portion of the crease-guide-lever toward that of the forepart-guide-lever, a slide movable between the contact-portions of the two levers and having a projection extending into the forepart-lever-opening, means for retracting the slide, a latch for retaining the slide against retraction, and a member variable in position upon the forepart-lever for engagement with the latch to release the slide.
